US00D736771S

(12) **United States Design Patent**
West et al.

(10) **Patent No.:** US D736,771 S
(45) **Date of Patent:** ** Aug. 18, 2015

(54) **WEARABLE ELECTRONIC DISPLAY**

(75) Inventors: **Adrian Mark Thomas West**, Newton, MA (US); **Zachary Jarrod Traina**, Hingham, MA (US); **Junggeun Tak**, Newtown Upper Falls, MA (US); **Thomas Gerard Parent**, Cambridge, MA (US)

(73) Assignee: **Kopin Corporation**, Westborough, MA (US)

(**) Term: **14 Years**

(21) Appl. No.: **29/425,890**

(22) Filed: **Jun. 28, 2012**

Related U.S. Application Data

(63) Continuation-in-part of application No. 29/360,498, filed on Apr. 27, 2010, and a continuation-in-part of application No. 13/092,485, filed on Apr. 22, 2011.

CLAIM

The ornamental design for a wearable electronic display, as shown and described.

DESCRIPTION

FIG. 1 is a perspective view of the wearable electronic display embodying the present design.

FIG. 2 is a front view of the wearable electronic display.

FIG. 3 is a rear view of the wearable electronic display.

FIG. 4 is a top view of the wearable electronic display.

FIG. 5 is a bottom view of the wearable electronic display.

FIG. 6 is a left side view of the wearable electronic display; and,

FIG. 7 is a right side view of the wearable electronic display. This article is a wearable electronic display.

The broken line showing of the headphones in FIG. 1 illustrates the environment of the claimed design and forms no part thereof. All other broken lines in FIGS. 1-7 illustrate portions of the wearable electronic display that form no part of the claimed design.

1 Claim, 5 Drawing Sheets
